TAPE MAGAZINE FOR A MAGNETIC TAPE RECORDER OR SIMILAR ARTICLE

Victor Sussin, Chicago, Ill., assignor to Radon Corporation, Chicago, Ill., a corporation of Illinois

Filed Oct. 29, 1963, Ser. No. 77,194

Term of patent 14 years

(Cl. D26—14)

Fig.1.

Fig.2.

Fig.3.

Fig.4.

Fig.5.

FIGURE 1 is a top plan view of a tape magazine for a magnetic tape recorder or similar article, showing one form of my new design wherein the conjunctive interconnecting rib and boss configuration is applied to a cartridge having a large number of side bays or indentations;

FIGURE 2 is a front elevational view of the form shown in FIGURE 1;

FIGURE 3 is an exploded perspective view of the form shown in FIGURE 1;

FIGURE 4 is a top plan view of a tape magazine for a magnetic tape recorder or similar article, showing another form of my new design wherein the conjunctive interconnecting rib and boss configuration is applied to a cartridge having a lesser number of side bays or indentations;

FIGURE 5 is a front elevational view of the form shown in FIGURE 4; and

FIGURE 6 is an exploded perspective view of the form shown in FIGURE 4.

The rear and side walls of both forms are substantially flat surfaces free of ornamentation;

The drawing figures are diagonally lined to indicate transparency;

The generic design characteristic feature common to all forms of the design resides in the disclosed angular array of ribs projecting from and interconnecting with circular protuberant portions of one or more of the surfaces, substantially as shown in FIGURES 1, 3, 4 or 6.

I claim:

The ornamental design for a tape magazine for a magnetic tape recorder or similar article, as shown and described.
